Filed Aug. 31, 1960, Ser. No. 61,969

Term of patent 14 years

(Cl. D13—1)

FIG. 1

2

FIG. 2

FIG. 3

FIGURE 1 is a front view of a decorative panel showing my new design. The line shading utilized on the flat surfaces and the bevel shading on the inclined faces are employed to represent contrasting flat and beveled surfaces;

FIGURE 2 is an enlarged cross-sectional view along the line 2—2 of FIGURE 1; and

FIGURE 3 is an enlarged fragmentary perspective view of the upper right section of FIGURE 1.

I claim:

The ornamental design for a decorative panel, substantially as shown and described.
